Nils A. Johanson, Clifton, N. J.

Application March 18, 1944, Serial No. 527,048

6 Claims. (Cl. 82—1)

The invention relates to milling machines and the like, and has for its object to provide a novel attachment capable of being readily combined with the machine and designed to increase the operative sphere of the latter.

The invention contemplates further the provision of a novel attachment for turning, facing and boring, arranged for easy and efficient combination with the milling machine or the like, to become an operative part thereof.

Another object of the invention is to provide a simple attachment which may be readily combined with a milling machine or the like to perform operations therein, heretofore, requiring elaborate and complicated equipment set up in a lathe.

Other objects will appear from the description hereinafter and the features of novelty will be pointed out in the claims.

In the accompanying drawings, which illustrate examples of the invention without defining its limits,

Fig. 1 is a side elevation of the novel attachment mounted in operative position in the milling machine or the like;

Fig. 2 is a front elevation of the attachment;

Fig. 3 is a rear elevation of the attachment on a larger scale and partly in section;

Fig. 4 is a longitudinal section on the line 4—4 of Fig. 3;

Fig. 5 is a detail sectional view of a clutch mechanism included in the attachment;

Fig. 6 is a horizontal sectional view on the line 6—6 of Fig. 4;

Fig. 7 is a detail elevation partly in section of the compound feed screw and associated parts;

Fig. 8 is an inverted plan view of the female member of a clutch included in the attachment;

Fig. 9 is a detail view of the upper end of the feed screw shown in Fig. 7 and looking at right angles thereto;

Fig. 10 is a perspective view of a bracket forming part of the attachment;

Fig. 11 is a side elevation of another form of the attachment, and

Fig. 12 is a rear view thereof.

The novel attachment in the form illustrated in Figs. 1 to 10 inclusive comprises a bracket 15 having its upper end split at 16 and provided with an opening 17, and a bolt 18 and nut 18—a whereby said bracket 15 may be clamped in place in the milling machine or the like, as will more fully appear hereinafter. The lower depending portion 19 of the bracket 15 is provided with a circular opening 20, internally threaded for the

accommodation of the externally-threaded section 21 of a tubular member or pedestal 22. The latter is provided with an annular bearing section 23 and a contiguous annular bearing section 24 of slightly larger diameter forming an annular shoulder 25, and further includes an annular flange 26 as shown in Figs. 1 and 5. An externally-threaded clutch ring 27 is mounted on the annular bearing section 23 and is rigidly clamped thereon between the annular shoulder 25 and the face of the depending portion 19 of the bracket 15, and an internally-threaded clutch sleeve 28 is rotatably mounted on the clutch ring 27 in threaded engagement therewith. The threads of the ring 27 and sleeve 28 are of the quick-acting type to enable said sleeve 28 to function as a feed clutch in the manner to be more fully set forth hereinafter. Any suitable means may be provided to facilitate the operation of the clutch sleeve 28, as for instance by providing the same with an outwardly-projecting handle 29 which may be detachably threaded into said sleeve 28. An annular feed clutch gear 30 is mounted on the bearing section 24 and is located between the clutch sleeve 28 and the annular flange 26 of the member or pedestal 22 as shown in Fig. 1. Dependent upon the position of the clutch sleeve 28, the feed clutch gear 30 is either fixed against rotation on the bearing section 24 or is free to rotate thereon. To facilitate the locking of the gear 30 by the clutch sleeve 28, the latter preferably is provided on its one face with an annular rib 28—a arranged to frictionally fit into an annular groove 30—a formed in the contiguous face of the gear 30 as shown in Fig. 5. To improve the action of the clutch mechanism the rib 28—a and groove 30—a may be beveled in complementary relation to each other. The attachment further includes a compound, comprising a block 31 provided on one face with an annular shoulder 32 from which a preferably tapering stem 32—a projects in perpendicular relation preferably as an integral part of the block 31. On its opposite face the block 31 is provided with a guide rib 33 which extends throughout the length thereof and is suitably formed along its opposite longitudinal edges in a manner to constitute a guide for the sliding movements of an associated slide 34. In the illustrated example the guide rib 33 is formed with undercut bevelled longitudinal edge surfaces 35 for this purpose, and the slide 34 is provided with co-operating undercut bevelled ribs 36 extending lengthwise thereof and arranged to slidably fit said edge surfaces 35 to thereby slidably mount the slide 34 on

the block 31 for the purpose to be more fully set forth hereinafter.

As shown in Figs. 3 and 4, the block 31 includes a recess 37, the opposite end walls of which are provided with threaded openings for the reception of threaded bearing bushings 38. A compound feed-screw 39 is rotatably mounted in said bushings 38 and at one end projects outwardly beyond the block 31 and is screw-threaded for the accommodation of a nut 40 whereby said feed screw 39 is fixed against relative lengthwise movement without interfering with its rotation relatively to said block 31. The opposite end of the feed-screw 39 extends beyond the opposite end wall of the recess 37 into an end chamber 41 open outwardly at the contiguous end of the block 31 as illustrated in Fig. 4. At said opposite end the feed-screw 39 is provided with one member of a clutch, as for instance the female clutch member 42 which comprises an annular sleeve 43 rotatably fitting the open end of the chamber 41 and a preferably knurled or otherwise roughened integral annular head 44 located outwardly beyond the end of the block 31 as shown in Figs. 1, 2, 3 and 4. The clutch member 42 is keyed upon the feed-screw 39 in any suitable manner as by means of projections 42—a or a conventional key or the like carried by the feed-screw 39 and extending into a groove 45 extending lengthwise interiorly of the clutch member 42. For the purpose of fixing the clutch member 42 in different positions on the feed-screw 39, the latter may be provided with a plurality of indentations 46 designed to receive the inner end of a set screw 47 carried by the clutch member 42 as shown in Fig. 7.

The clutch member 42 is suitably designed for cooperation with an associate male clutch member 48, and for this purpose may have the inner end portion of the sleeve 43 provided interiorly with a plurality of open-ended recesses 49 as illustrated in Fig. 7. The associate male clutch member 48 is loosely mounted on the feed-screw 39 within the chamber 41 and at its inner end carries a worm gear 50, which preferably constitutes an integral part of the male clutch member 48 and in any case rests rotatably upon the one bearing bushing 38 as shown in Fig. 4. The male clutch member 48 in addition includes a plurality of teeth 51 or their equivalent designed to fit into and co-operate with the recesses 49 of the female clutch member 42 to operatively connect the male clutch member 48 and gear 50 with the feed-screw 39 as will appear more fully hereinafter.

The worm gear 50 meshes with a worm pinion 52 fixed upon a worm-shaft 53 rotatably mounted respectively in the block 31 itself and in a bearing bushing 54 threaded into the same as illustrated in Fig. 6. The worm-shaft 53 projects outwardly beyond the bushing 54 and exteriorly thereof carries a pinion 55 which may be fixed to rotate with said shaft 53 in any convenient manner as by means of a set screw 56.

To enable the feed-screw 39 to be manually operated at will, an operating handle 39—a may be provided as shown in Figs. 1 and 2, and removably fitted upon the end of said feed-screw 39 and coupled thereto in any conventional manner as by means of pins 39—b on the feed-screw 39 and cooperating recesses on the handle 39—a into which said pins 39—b are arranged to fit.

In the operative assembled condition of the compound the slide 34 is slidably mounted upon the guide rib 33 of the block 31 as illustrated in Fig. 6. In the preferred arrangement a metal or other strip 57 is located between the one edge 75

surface 35 of the rib 33 and the contiguous surface of one rib 36 of the slide 34. For the purpose of adjusting the strip 57 to take up wear and to adjust the braking effect thereof, the block 31 may be provided with a plurality of set screws 58 bearing against said strip 57 and fixed in adjusted positions by lock-nuts 59. In order to slidably operate the slide 34, the latter is provided on its inner surface with an internally-threaded block or nut 60 secured in place by screws 61 or the like, and in threaded engagement with the intermediate threaded portion 62 of the feed-screw 39 as shown in Fig. 4.

The slide 34 is further provided with suitable means for carrying the tool selected for performing any given operation within the range and scope of the attachment. In the illustrated example the aforesaid means comprises a tool-holder having a base-plate 63 and a tool-socket 64 located thereon in perpendicular relation as shown in Figs. 1, 4 and 6. The tool-socket 64 is designed to receive and hold the selected tool 65 which may be removably secured in place in any suitable manner as by means of one or more set screws 66.

Suitable means is provided for movably mounting the tool-holder in any one of a plurality of positions on the outer face of the slide 34. In the illustrated example the base-plate 63 accordingly is provided with a plurality of openings 67 arranged in co-operating pairs in spaced parallel rows and adapted to register with threaded apertures 68 located in corresponding pairs in corresponding spaced parallel rows on the front face 35 of the slide 34. Screws 69 designed to pass through the openings 67 and into threaded engagement with the apertures 68 serve to movably secure the base-plate 63 in surface engagement with the face of the slide 34 and thereby mount the tool-holder in position thereon.

To mount the attachment in the milling machine or the like, the bracket 15 may be clamped upon a rod 70 located at the upper end of the pedestal or column 71 of the milling machine or the like, so as to depend thereon in surface engagement with said pedestal or column 71 as shown in Fig. 1. The feed-clutch and associate elements which may be combined with the bracket 15 either prior to or subsequently to its mounting in the milling machine or the like, are thereby suspended in said machine at a distance above the conventional reciprocating table thereof.

The compound may then be placed in position by inserting the stem 32—a axially through the flange 26 and the tubular member or pedestal 22 into frictional or other connection with the conventional driving spindle A of the milling machine as shown in Fig. 1, and fitting the annular shoulder 32 into said tubular pedestal 22 which said shoulder fits snugly. At the same time the pinion 55 is brought into mesh with the feed-clutch gear 30, as shown in Fig. 1, to thereby mount the selected tool 65 in operative position in the machine ready for predetermined service therein.

Instead of following the above procedure in combining the attachment with the milling machine, all parts of said attachment may be assembled and mounted on the bracket 15, and the latter then clamped in place in the milling machine as set forth above. When the whole attachment, in the form of a complete unit, is mounted in the milling machine, the stem 32—a is connected with the conventional driving spin-

idle A thereof in the same way as previously described.

In the final analysis, regardless as to which of the foregoing proceedings or any other is followed, the attachment is mounted in the milling machine in operative connection with the driving spindle A of said machine.

During an operative period, a power rotation of the driving spindle A will cause the stem 32-a to be rotatively driven on its axis, with the annular shoulder 32 serving as a bearing in the tubular pedestal 22. The rotation of the stem 32-a correspondingly rotates the compound comprising the block 31, slide 34 and associate elements, and causes the tool 65 to develop operative functions dependent upon its position on the slide 34 and upon the setting of the clutch sleeve 28.

If the latter occupies its left hand position in Figs. 1 and 5, in which the annular rib 28-a of the sleeve 28 is disengaged from the annular groove 30-a, the feed clutch gear 30 will be free to rotate on the bearing section 24. Under such conditions the pinion 55 being in mesh with the gear 30 will simply cause the latter to rotate on bearing section 24 without bringing about any rotation of the pinion 55 on its own axis. As a result the worm shaft 53, and worm pinion 52 also do not rotate about their common axis and no rotative operation of the worm gear 50 on its own axis takes place, with the result that the feed-screw 39 also remains stationary, insofar as relative rotative movement on its own axis is concerned. The slide 34 consequently does not move relatively to the block 31 and the tool 65 remains in a given position on the compound and performs its functions accordingly.

If the operation being performed by the tool 65 requires it, the feed-screw 39 may be relatively rotated on its axis in the following manner. A downward pressure on the handle 29 rotates the clutch sleeve 28 on the relatively stationary clutch ring 27 which, through the co-operation of the screwthreads of said ring 27 and sleeve 28 shifts the latter to the right to the position shown in Fig. 5 and forces the annular rib 28-a into the annular groove 30-a in frictional engagement therewith. As a result the feed clutch gear 30 is locked against relative rotative movement on the bearing section 24.

Under such conditions, as the compound is rotated as previously described by the operation of the driving spindle A and stem 32-a, the pinion 55 is caused to roll upon and travel circumferentially of the stationary gear 30. As this takes place, the pinion 55 in its travel about the gear 30 is caused to rotate on its own axis and thereby correspondingly rotates the worm-shaft 53, and worm pinion 52 and thereby rotatively actuates the worm gear 50. If, at the time the clutch members 42 and 48 are in engagement with each other, as shown in Fig. 7, the operation of the worm gear 50 will actuate the feed screw 39 and thereby cause the nut 60 and with it the slide 34 and associated tool-carrying means to be slidably shifted on the block 31. The tool 65 will thereby be radially shifted coincidentally with its operation in circular paths.

When the male clutch member 48 is disengaged from the female member 42, which may be done by shifting the latter manually on the feed-screw 39, the latter will not be rotated on its axis, due to the fact that at this stage the male clutch member 48 is loose and simply rotates on said feed-screw 39. Under such conditions, the

latter may be manually operated by means of the annular head 44, which further serves to manually shift the female clutch member 42 into and out of engagement with the male clutch member 48 at will. The rotation of the feed-screw 39 and the consequent radial operation of the slide 34 and tool 65 may accordingly be correspondingly controlled at will.

In the form shown in Figs. 11 and 12 the novel attachment includes means whereby the operation of the feed-screw 39 may be controlled as to direction of feed and whereby different feed speeds may be provided.

The attachment in this form generally speaking may be constructed and arranged in the same way as the one first described, and includes the feed-screw 39 and worm gear 50 which as in the first form meshes with the worm pinion 52 on the worm-shaft 53. The latter, as in the form first described carries a pinion 55 located exteriorly of the block 31. The form of the attachment under discussion may also include all of the other elements shown in the form first described and operating and functioning in the same way.

The feed clutch gear 30 instead of meshing directly with the pinion 55 as in the first form, is in mesh with a gear 72 mounted on the block 31 preferably in a slot 73 so as to be capable of being set in various positions thereon for the purpose to be more fully described hereinafter. The gear 72 meshes with a gear 74 mounted on the block 31 and compounded with a pinion 75 carried by the same shaft which carries the gear 74.

A reverse lever 76 is mounted on the block 31 to pivotally swing about the common axis of the gear 74 and pinion 75 and preferably terminates in a handle 77 to facilitate its pivotal operation. The lever 76 carries a gear 78 which meshes with the pinion 75 and with a gear 79 also mounted on said lever 76. The gears 78 and 79 are arranged to be selectively caused to mesh with the pinion 55 by manipulating the reverse lever 76 to thereby determine the direction of rotation of the feed screw 39. The lever 76 is provided with an arcuate slot 80 for the accommodation of a threaded stem 81 carried by the block 31 and adapted to receive a nut 82 whereby the reverse lever 76 may be fixed in its adjusted position.

In the position of the lever 76 illustrated in Fig. 12 the gear 79 is disconnected from the pinion 55 and the gear 78 is in mesh therewith to thereby operate the feed screw 39 in one direction. By pivotally shifting the lever 76 downwardly from the position shown in Fig. 12, the gear 78 will be disconnected from the pinion 55, and the gear 79 will be adjusted into mesh therewith. This causes the train of gearing to operate the feed screw 39 in the opposite direction.

That is to say, with the gear 30 locked against rotation as hereinbefore set forth and the compound being rotated by the operation of the driving spindle A and stem 32-a, the train of gearing and lever 76 will be operated in a circular path, with the gear 72 travelling circumferentially of and in meshed rolling engagement with the gear 30. The gear 72 will thereby be rotated on its own axis and by transmission through the gear 74, pinion 75, and gear 78 will actuate the pinion 55 to operate the feed-screw 39 in said one direction.

After the lever 76 has been shifted downwardly as above stated, the gear 72 in its travel

circumferentially of and in meshed rolling engagement with the fixed gear 30, will drive the gear 74, pinion 75 and gear 78 which in this setting is out of mesh with the pinion 55. The gear 78 will, however, operate the gear 79 and through it the pinion 55 in a reverse direction to correspondingly operate the feed screw 39 in the aforesaid opposite direction.

As a result of the above changes in the direction of rotation of said feed-screw 39, the operations of the elements associated therewith will be correspondingly reversed. The operation of the feed-screw 39 and its co-operating elements may thus be selectively controlled in accordance with the requirements of the particular operations being performed by the attachment at any given time to secure the desired operative results in a simple and efficient manner.

By substituting gears 74 of varying diameters, and adjusting the position of the gear 72 to correspond the speed of operation of the feed-screw 39, in either direction, may be selectively varied at will to meet any existing or predetermined conditions of operation.

The attachment is easily installed in a milling machine or the like and when so installed has many uses. For example:

Boring may be done thereby on holes with shoulders and steps of different dimensions and depths, the accuracy of which may be acquired by a graduated adjustment on the compound block.

Facing of shoulders or flanges inside of holes may be readily accomplished by means of the mechanical feed of the attachment. It may also be used for facing outer flanges, shoulders, or for any other type of facing within its operative range. The attachment in addition may be used for turning outside diameters of different depths and dimensions.

As a matter of fact, the attachment is of material value to shops engaged in work requiring boring, facing and turning of bulky and odd-shaped castings which normally are performed by setting up elaborate fixtures and equipment on lathes.

Although the present invention has been described in conjunction with preferred embodiments, it is to be understood that modifications and variations may be resorted to without departing from the spirit and scope of the invention, as those skilled in the art will readily understand. Such variations and modifications are considered to be within the purview and scope of the claims.

I claim:

1. An attachment for milling machines and the like comprising a bracket adapted to be removably mounted in the machine, a tubular pedestal carried by said bracket in perpendicular relation thereto, a feed-clutch gear rotatably mounted on said pedestal, a clutch on said pedestal whereby said clutch gear is selectively locked against movement on said pedestal or released for rotation thereon, a hollow block, a stem carrying said block whereby the latter is rotatably carried by said pedestal and releasably connected with the driving spindle of said machine for rotation thereby, a feed screw mounted interiorly of said block, a worm gear loosely mounted on said feed screw, and including one member of a clutch, a co-operating clutch member mounted to rotate with said feed screw and manually adjustable thereon to connect and disconnect said clutch members at will, a worm shaft journaled in said block and projecting exteriorly

thereof, a worm pinion on said shaft in mesh with said worm gear, a pinion fixed on the projecting portion of said worm shaft and meshing with said feed clutch gear, said pinion circumferentially rolling upon said clutch gear when locked against movement to thereby operate said feed screw, and otherwise rotating said clutch gear without operation of said feed-screw, a slide slidably mounted on said block for rotation therewith, and operatively connected with said feed-screw for slideable operation thereby when the latter is operated, and a tool removably mounted on said slide and partaking of the operative movements thereof.

2. An attachment for milling machines and the like comprising a bracket adapted to be removably mounted in the machine, a tubular pedestal carried by said bracket in perpendicular relation thereto, a feed-clutch gear rotatably mounted on said pedestal, a clutch on said pedestal whereby said clutch gear is selectively locked against movement on said pedestal or released for rotation thereon, a hollow block, a stem carrying said block whereby the latter is rotatably carried by said pedestal and releasably connected with the driving spindle of said machine for rotation thereby, a feed screw mounted interiorly of said block, actuating means carried by said block in operative connection with said feed-clutch gear and operated thereby when said gear is locked against movement to actuate said feed-screw and to leave the latter inactive when said feed-clutch gear is free to rotate, a carrier rotatable with said block and slideable relatively thereto, said carrier being operatively connected with said feed-screw, and a tool removably mounted on said carrier and partaking of the operative movements thereof.

3. An attachment for milling machines and the like comprising a bracket adapted to be removably mounted in the machine, a tubular pedestal carried by said bracket in perpendicular relation thereto, a feed-clutch gear rotatably mounted on said pedestal, a clutch on said pedestal whereby said clutch gear is selectively locked against movement on said pedestal or released for rotation thereon, a compound rotatably mounted on said pedestal and operatively connected with the driving spindle of said machine for rotation thereby, a tool removably mounted on said compound, said tool partaking of the rotative movements of the compound and being slideable relatively thereto, and means co-operating with said feed-clutch gear whereby the relative sliding movements of the tool may be selectively controlled.

4. An attachment for milling machines and the like comprising a bracket adapted to be removably mounted in the machine, a tubular pedestal carried by said bracket in perpendicular relation thereto, a feed-clutch gear rotatably mounted on said pedestal, a clutch on said pedestal whereby said clutch gear is selectively locked against movement on said pedestal or released for rotation thereon, a hollow block, a stem carrying said block whereby the latter is rotatably carried by said pedestal and releasably connected with the driving spindle of said machine for rotation thereby, a feed screw mounted interiorly of said block, a worm gear loosely mounted on said feed screw, and including one member of a clutch, a co-operating clutch member mounted to rotate with said feed screw and manually adjustable thereon to connect and disconnect said clutch members at will, a worm shaft journaled in said block and projecting exteriorly

members at will, a worm shaft journalled in said block and projecting exteriorly thereof, a worm pinion on said shaft in mesh with said worm gear, a pinion fixed on the projecting portion of said worm shaft, a train of gearing connected with said pinion and including a gear meshing with and circumferentially rolling upon said clutch gear when locked against movement to thereby operate said feed screw, and otherwise rotating said clutch gear without operation of said feed screw, means for selectively adjusting said train of gearing to reverse the direction of rotation of said feed screw, tool-carrying means on said block in operative connection with said feed screw, and a tool removably mounted on said tool-carrying means for operation thereby.

5. An attachment for milling machines and the like comprising a bracket adapted to be removably mounted in the machine, a feed-clutch gear rotatably mounted on said bracket, means for selectively locking said feed-clutch gear against rotating, a compound movably carried by said bracket for connection with the driving means of said machine, a feed-screw carried by said compound, tool-carrying means movably mounted on said compound in operative connection with said feed-screw, a tool removably carried by said tool-carrying means, a pinion on said compound operatively connected with said feed-screw, a main

5 gear on said compound meshing with said feed-clutch gear and operated thereby when said clutch gear is locked against operation, a train of gearing connecting said main gear with said pinion, and means for selectively adjusting said train of gearing to reverse the direction of operation of said feed screw.

10 6. An attachment for milling machines and the like comprising a bracket adapted to be removably mounted in the machine, a feed-clutch gear rotatably mounted on said bracket, means for selectively locking said feed-clutch gear against rotating, a compound movably carried by said bracket for connection with the driving of said machine, a feed-screw carried by said compound, tool-carrying means movably mounted on said compound in operative connection with said feed-screw, a tool removably carried by said tool-carrying means, a pinion on said compound operatively 15 connected with said feed-screw, a main gear on said compound meshing with said feed-clutch gear and operated thereby when said clutch gear is locked against operation, a train of gearing connecting said main gear with said pinion, and a lever pivotally mounted on said compound and carrying said train of gearing for selectively adjusting the latter to reverse the direction of operation of said feed screw.

NILS A. JOHANSON.
